UNITED STATES PATENT OFFICE.

JAMES IRWIN, OF SOUTH SAN FRANCISCO, CALIFORNIA, ASSIGNOR TO H. J. MAHONY CO., OF SAN FRANCISCO, CALIFORNIA, A CORPORATION OF CALIFORNIA.

RELEASING DEVICE.

1,227,147.

Specification of Letters Patent. Patented May 22, 1917.

Application filed February 19, 1916. Serial No. 79,352.

To all whom it may concern:

Be it known that I, JAMES IRWIN, a citizen of the United States, residing at South San Francisco, county of San Mateo, and State of California, have invented new and useful 5 Improvements in Releasing Devices, of which the following is a specification.

This invention relates to a releasing device.

One of the objects of the present invention 10 is to provide a simple, substantial, easily operated releasing device capable of quickly releasing suspended bodies from their supports or mountings, and which is especially 15 adapted for use in connection with life boats and the like to permit the same to be quickly released from the tackle or davits from which they are suspended. Another object 20 of the invention is to provide means for simultaneously operating two releasing devices, for instance, one at each end of a boat, and, furthermore, to provide a releasing device which may be released either with or 25 without relieving the load. Further objects will hereinafter appear.

The invention consists of the parts and the construction and combination of parts as hereinafter more fully described and claimed, having reference to the accompanying drawings, in which—

Figure 1 is a central, vertical section through the releasing device.

Fig. 2 is an end view of same.

Fig. 3 is a longitudinal section of a life 35 boat, showing the application of the invention.

Fig. 4 is an enlarged cross section on line 4—4 of Fig. 3.

Fig. 5 is an enlarged cross section on line 40 5—5 of Fig. 3.

Referring to the drawings in detail, A indicates a pair of spaced side plates, which, in the instance, are connected on one side by a web 2, formed integrally therewith, and 45 on the other side by a cross bar 3. The side plates thus connected form an open slot 4, at the upper end, and the lower end is also open to permit access to the intermediate space, as will be hereinafter described.

50 Pivotaly mounted on a pin 5, secured between the plates, is a hook-shaped bill 6, on the lower end of which is formed a shank 7. The hook is so positioned as to extend across the slot 4, when closed, but is permitted to 55 swing back into the dotted line position shown at 6^a when opened. Pivotaly mount-

ed on a pin 8, secured between the side plates, is a horizontally positioned lever 9, on which is formed a shoulder or cam projection 10 provided for the purpose of engaging and locking the shank 7 of the hook. One end of the lever is extended beyond the pivotal point 8, as at 11, to reach beyond the plates and is adapted to form a lock with a removable wedge member 12. The member 65 12 is adapted to be interposed between the lever extension 11 and a projecting flange 13 formed on the cross-bar 3.

Pivotaly mounted between the side plates, near the lower end on a pin 14, is a locking 70 lever 15. One end of this lever is adapted to engage the underside of the lever 9; and the opposite end is adapted to be connected with a link 16 which is connected with a bell-crank 17, pivotaly mounted, as at 18, on a 75 bracket secured on the keel of the boat indicated at B.

The releasing device, comprising the connected side plates, the hook 6 and the interlocking levers 9 and 15, may be secured to 80 the bow and stern of the boat in any suitable manner, but preferably to a plate 17' which is bolted in position and which is provided with two pair of outwardly extending lugs 85 18 and 19. These lugs embrace the upper and lower ends of the side plates, and bolts 20, passing through the lugs and the side plates, form a secure connection between the releasing device and the plate 17'.

Positioned centrally of the boat, or in any 90 other convenient position, is a vertically disposed frame 22, in the upper end of which is slidably mounted a rod 23 provided with a handle 24. The rod is preferably round in cross section and provided with a pair of 95 wing extensions 25 (see Figs. 3 and 5), and the upper end of the frame is similarly shaped, that is, a round opening fitting the rod 23 is provided and a pair of slots, similar in shape to the wing extensions 25, is 100 provided to permit the rod to be lowered, as will hereinafter be described.

Mounted on the lower end of the rod is a bracket 26, and pivotaly mounted in the lower end of the frame 22 is a pair of offset 105 bell-cranks 27 and 28 which are connected with the bracket 26, by means of a pair of links 29 and 30. Interposed between each bell-crank 27 and 28 and the bell cranks 17, mounted at each end of the boat, is a rod 31 110 32 which extends through a pipe 32 secured upon the keel of the boat.

The operation of the device will be as follows: With the boat suspended by a tackle from davits, or any other suitable support, it is possible to lower the boat until it is floated upon the water when it may be released by turning the rod 23, by means of the handle, until the wing projections 25 register with the similarly shaped slots in the upper end of the frame 22. The rod 5 will then permit a rocking of the bell-cranks 27 and 28, with connected bell-cranks 17, thereby allowing these to swing the locking levers 15 from the dotted line position shown at 15^a in Fig. 1 to the full line position. The cam lever 9, being released, will then drop down in unison with the locking lever and release the hook, permitting this to swing free and release the tackle. The arrangement of the locking 10 levers also permits the boat to be released while still in suspension. As the weight of the load is carried by the hook, it will be seen that the hook always has a tendency to swing inward in the direction of arrow *a* and therefore has a constant tendency to depress the cam lever 9 and rock the locking lever 15 into the full line position. It is, 15 therefore, only necessary to turn the rod 23 until the wing projections 25 register with 20 the slots in the frame 22.

The pressure of the shank 7, against the cam levers 9 and locking levers 15, will then force this in a downward direction and pull the rod 23 down, permitting a simultaneous 25 releasing action of both hooks.

A releasing device constructed as here shown is simple, rigid and substantial in construction and is always positive in action as it cannot fail to release either with or 30 without a load if the operating requirements are complied with.

An important feature of the present invention is the position of the hook and locking levers. This arrangement causes 35 the hooks to move, when released, with and not against the weight. The provision of the operating rod 23, which is inclosed by the frame 22, positively prevents accidental releasing of the hooks as these cannot be 40 come released except by the man in charge, and as he must deliberately turn the rod until the wing projections 25 register with the slots in the casing or frame 22, it can be seen that accidental release cannot take 45 place. The weight or pressure exerted upon the levers 9 and 15, the bell-cranks 17, 27 and 28, and the intermediate connecting rods, causes the operating rod to drop its full distance into the frame 22 instantly 50 when it is turned into register with the slots or keyway in the frame. The weight or pressure constantly exerted is so reduced, through the arrangement of the leverage between the different pivotal points, that 55 only a small fraction of the load is trans-

mitted at any time, thus removing any danger of bending the rods and accidentally releasing the hooks at any time.

The secondary lock, formed by the removable wedge 12, is only provided for the purpose of permitting one man to engage the hooks and lock the same with relation to the tackle. It can easily be seen that one man could not possibly engage both hooks at one time as these are placed at opposite ends of the boat. He will, therefore, have to engage one hook and then interpose the wedge 12 to temporarily retain it in locked position. He may then proceed to the opposite end of the boat and engage and lock the other hook in the same manner. He next proceeds to the center of the boat and pulls the rod 23 in an upward direction and locks it in this position, when fully extended, by turning the wing projections out of register with the keyway or slots in the frame. This upward movement of the rod moves the connected levers and interposed links to locked position and will also release the wedges 12 as these are connected by chains 12^a with the links 16. The temporary locking wedges are thus automatically released, when the hooks are locked in the proper manner, and the chains connected to same are so short that they cannot again be inserted when the rod 23 is in the raised locked position shown. This is very essential as one or both wedges might possibly be left in locking position, thus permitting one end only to become released when the rod 23 is operated or some other accident might happen which could otherwise have been avoided.

The materials and finish of the several parts of the device are such as the experience and judgment of the manufacturer may dictate.

I wish it understood that various changes in form, proportions and details of construction may be resorted to within the scope of the appended claims and that I do not wish to limit myself to the specific design and construction here shown.

Having thus described my invention, what I claim and desire to secure by Letters Patent is—

1. The combination with a pair of releasing devices and the locking levers carried thereby, of a releasing rod interposed between the locking levers, a frame in which the releasing rod is vertically positioned and slidably mounted, a bracket on the lower end of the rod, a pair of bell-cranks each connected with a respective one of the releasing devices, and a pair of rods connecting the bracket and the bell cranks.

2. A releasing device comprising a pair of spaced connected plates, a hook member pivotally mounted between the plates having a shank extension on one side of the pivot,

a cam lever pivotally mounted between the plates and engageable with the shank extension on the hook to lock the hook against movement, a locking lever movable independently of and engageable with the cam lever, and means for locking the locking lever against movement.

3. A releasing device comprising a pair of spaced connected plates, a hook member pivotally mounted between the plates having a shank extension on one side of the pivot, a cam lever pivotally mounted between the plates and engageable with the shank extension on the hook to lock the hook against movement, and a removable wedge member insertible between the cam lever and a lug formed between the side plates to lock the cam lever against movement.

4. A releasing device comprising a pair of spaced connected plates, a hook member pivotally mounted between the plates having a shank extension on one side of the pivot, a cam lever pivotally mounted between the plates and engageable with the shank extension on the hook to lock the hook against movement, a removable wedge member insertible between the cam lever and a lug formed between the side plates to lock the cam lever against movement, a locking lever engageable with the cam lever, means for locking the locking lever against movement, and means for automatically retracting the wedge member when the locking lever is moved into locking position and locked.

35 5. A releasing device comprising a pair of spaced connected plates, a hook member pivotally mounted between the plates having a shank extension on one side of the pivot, a cam lever pivotally mounted between the plates and engageable with the shank extension on the hook to lock the hook against movement, means for locking the cam lever against movement, and a securing member

adapted to carry the releasing device as a whole, said member comprising a plate, a 45 pair of lugs formed on each end of the plate and adapted to embrace the side plates of the releasing device, and bolts extending through the lugs and side plates to secure the releasing device.

6. A releasing device comprising a movably supported engaging member normally inoperative, a support therefor, a locking wedge insertible between the member and support for holding the member operative, means movable to engage said member to 55 hold the same operative, and means operable by and during movement of said first means to operative position for rendering the wedge inoperative.

7. The combination with a pair of releasing devices and the locking levers carried thereby, of a releasing rod interposed between the locking levers, a frame in which the releasing rod is vertically positioned and slidably mounted, cranks and links connecting the lower end of the releasing rod with the locking levers to transmit movement from the releasing rod to rock the locking levers simultaneously into releasing or locking position, a pair of wing extensions on 70 the releasing rod and slots in the frame with which said wing extensions are adapted to register, and means for turning the releasing rod to bring the wing extensions out of register with the slots and to lock the rod 75 against sliding movement when the locking levers are in locking position.

In testimony whereof I have hereunto set my hand in the presence of two subscribing witnesses.

JAMES IRWIN.
